UNITED STATES PATENT OFFICE.

DELBERT H. SNAVELY, OF AMHERST, OHIO.

HOLSTER.

1,148,935.

Specification of Letters Patent.

Patented Aug. 3, 1915.

Application filed February 20, 1915. Serial No. 9,548.

To all whom it may concern:

Be it known that I, DELBERT H. SNAVELY, a citizen of the United States, residing at Amherst, in the county of Lorain and State 5 of Ohio, have invented certain new and useful Improvements in Holsters; and I do hereby declare the following to be a full, clear, and exact description of the invention, such as will enable others skilled in 10 the art to which it appertains to make and use the same.

My invention relates to holsters for carrying pistols, more especially automatic pistols or other small fire arms.

15 The principal object of my invention is to provide means which can be carried upon the person, preferably upon a belt, in which a pistol, especially an automatic pistol, can be conveniently carried and readily removed.

20 I also aim to provide means in which the pistol can be quickly and conveniently mounted, and in which upon its removal, there will be no, or a minimum, danger of accidentally injuring or discharging the 25 pistol.

I also aim to provide means in which the more delicate parts of the instrument, such as the sights and the more vital parts, such as the safety, are protected while in the 30 holster, even against the most violent jars which may be conveyed to the holster in use.

I further provide means for removably holding the pistol in the holster, so that while it cannot be readily jarred or accidentally jerked out, it can be quickly removed by the user. The pistol should also be prevented from jumping about in the 35 holster, and this I aim to do. I also aim to accomplish these means, at the same time providing a device which can be conveniently and cheaply made, and which furnishes ample protection to the fire arm when being carried upon the person.

40 Other objects of my invention and the invention itself will probably be better understood from a description of a specific embodiment of the invention, one of which is illustrated in the annexed drawing.

Figure 1 is a side elevation of an embodiment of my invention, showing certain parts of the embodiment in dotted lines. Fig. 2 is a side elevation taken at right angles to the elevation shown in Fig. 1. Fig. 3 is a bottom plan view of the embodiment shown 55 in Fig. 1 and Fig. 2. Fig. 4 is a plan view

of a block used in the embodiment of my invention illustrated.

Referring now to the embodiment of my invention illustrated in the drawings, at 6 is shown the main casing of the holster 60 which may be made of any suitable material, such as leather. This casing is formed by coiling the leather into the desired shape. In the form shown, the casing is rectangular in cross-section, and upon the outside consists of one thickness of the material and on the inside, as shown at 6₁ and 6₂, of two plies of the material. The sides of the casing are closed by fastening the plies 6₁ and 6₂ together by any suitable means, such as 65 rivets or sewing, all of which is so well known that it has not been illustrated. This method leaves the outside of the holster free from the fastening means, which makes it more attractive in appearance and lessens 70 the danger of the clothes being caught thereon.

The front of the casing is closed, as shown in Fig. 1, but a large slot 14, of suitable shape, is cut in the back of the casing for 80 the entry and withdrawal of the fire arm. The bottom and top of the backside, however, are closed, as indicated at 14₁ and 14₂, preferably by material integral with the main piece from which the casing is made, 85 as previously described.

Means are provided for retaining the fire arm in the casing, here shown as a spring-pressed plunger mounted in the bottom of the casing. This plunger is shown at 3 and 90 the spring which normally presses the same upward is shown at 1. I prefer to mount these in a cell 13 formed by some stiff material, such as sheet metal, and mounted in the bottom of the casing. The spring, here 95 shown as a coil spring, abuts at one end against the plunger and at the other end against the bottom 2 of the casing. The upward movement of the plunger may be limited in some suitable way, such as by 100 using a spring expandible only as far as it is desired the plunger shall rise in the casing.

The sheet metal forming the cell 13 is fastened to the wall of the main casing in any 105 suitable way, such as by a rivet 4. The top of the casing is closed by a member 10. The means for retaining the fire arm in the holster may also include a block 8 mounted in the top of the casing and suitably shaped 110

for coöperation with the plunger. In the embodiment shown, this block is provided with a recess 20 and a curved shoulder 21, for a purpose to be explained.

5 Means are provided for attaching the holster to the belt or other device by which it is to be connected to the person of the user. This means is here shown as a belt loop 11 provided with a plurality of slots

10 15, through which a belt may be inserted. The member 11 is connected in any suitable manner to the casing proper. I may also employ a suitable metallic band 9 for protecting the top of the casing.

15 Means are provided for protecting the sights of the fire arm when it is in the holster, which here consists of a block 5, which prevents the sights from striking against the interior of the front wall of the

20 casing. This block may also coöperate in retaining the fire arm within the holster, as will be described, and as is illustrated in Fig. 1. In the particular form shown, the inner of the two plies of material forming

25 the inside wall of the casing is cut away at 7 to afford a protection for the safety device of the fire arm. The edges of the opening 7 engage the side of the fire arm and prevent the safety device from striking the 30 side of the chamber, as will readily be apparent. The bottom of the casing is closed by a member 16, as illustrated in the drawing.

When it is desired to insert the fire arm 35 into the holster, the muzzle is placed against the plunger 3, and the same is depressed by forcing the muzzle downward to such an extent that the butt end 30 of the fire arm

40 clears the edge 31 of the opening 14. The fire arm is then inserted in the casing, the barrel engaging the block 5. The plunger 3 being spring pressed upward, forces the butt 30 of the fire arm into the chamber formed by the casing wall and the recess 20 in the

45 block 8, the wall of the shoulder 21 camming the butt of the fire arm up into this recess. The back of the butt engages the shoulder 19, and the spring always maintaining a pressure upon the fire arm, it will be securely

50 held in the holster in the position shown in Fig. 1, against any treatment to which it may be subjected. When it is desired to remove the fire arm, pressure is applied to the stock 12 and the fire arm is forced downward, compressing the spring 1, until the butt of the fire arm clears the edge of the shoulder 19, when it can be readily withdrawn in the same manner in which it was inserted.

55 60 It will be readily understood that the shape of the parts may be modified to meet special kinds of fire arms; for example, the shape of the block 8 may be varied and in Fig. 4 I have illustrated a block which may be employed where 45 or 38 caliber hammer

fire arms are to be used. In this form the block is provided with a recess 40 and with projections 17 and 18, each of which is inclined so that the butt of the fire arm will be cammed either way into this recess and force the hammer into the recess 40, protecting the same, for example, by engaging the butt of the fire arm with the walls of the projections 17 and 18.

65 It will also be understood that other parts of the embodiments illustrated may be modified. In fact, I have shown this special embodiment for the purpose of explaining my invention, and not that I wish to be limited thereto, as many departures may be made 80 from the particular embodiment illustrated and from the details thereof, without departing from the spirit of the invention.

I claim:—

1. In a pistol holster, the combination of a 85 casing for the pistol having closed ends and an opening in its side for the insertion and withdrawal of the pistol and apparatus including a spring-pressed member for holding the pistol in the holster.

2. In a pistol holster, the combination of a casing for the pistol having an opening in one of its sides for the insertion and withdrawal of the pistol, a block in one end of the casing having a recess for the inclosure 95 of a portion of the pistol when the same is mounted in the holster, and a spring-pressed member in the other end of the casing to engage the other end of the pistol and force a portion thereof into the recess in the block. 100

3. In a pistol holster, the combination of a casing for a pistol having an opening in the back side thereof for the insertion and withdrawal of the pistol, a block in said casing having a recess therein, a spring-pressed plunger in said casing adapted to force one end of the pistol into said recess and a cam surface for directing such end of said pistol in said recess.

4. In a pistol holster, the combination of 110 a casing for a pistol having an opening therein, a recessed block and a spring-pressed plunger for retaining the pistol in the casing and means to prevent the pistol sights from engaging the walls of the casing.

5. In a pistol holster, the combination of a casing having an opening in the back side thereof for the insertion and withdrawal of the pistol, and means to removably secure the pistol in the casing, including a spacing block adapted also to prevent the pistol sights engaging the walls of the casing.

6. In a pistol holster, the combination of 125 an elongated, rectangular casing having the larger part of its rear side wall cut away to form an opening for the insertion and withdrawal of the pistol, a recessed block in the top of the casing, means forming a chamber 130

- in the bottom of the casing, a spring-pressed plunger in said chamber adapted to engage the muzzle of the pistol and force the butt end into said recess, said block being provided with a cam surface to direct said pistol butt into said recess and a spacing block on the interior wall of the front side of the casing adapted to engage the pistol barrel between the pistol sights to prevent the sights engaging the casing and to limit the forward movement of the pistol in said casing.
7. In a pistol holster, the combination of a parallelepiped shaped casing having a closed top and a long opening in one side thereof for the insertion and withdrawal of the pistol and means in the casing to engage and removably hold the pistol in the casing.
8. In a pistol holster, the combination of a casing formed by coiling a sheet of material, means fastening the ends thereof together, closed ends for said casing, said casing having a long slot in one of its walls for the insertion and withdrawal of the pistol, and means in said casing to removably hold the pistol in the casing.
9. In a pistol holster, the combination of a casing having closed ends and an opening therein for the insertion and withdrawal of the pistol, apparatus mounted in the casing but independent thereof for firmly holding the pistol in the casing but permitting ready removal thereof.
10. In a pistol holster, the combination of a casing formed by coiling a sheet of material, means to connect the ends of the sheet together, end pieces for said casing, said casing being provided with an opening in one of its side walls for the insertion and withdrawal of a pistol, a block in one end of said casing, a spring-pressed plunger in said casing for engaging one portion of the pistol and forcing another portion into said recess, and a cam for directing such second named portion of the pistol into said recess, whereby the pistol is removably held in the holster.
11. In a pistol holster, the combination of a casing having closed ends and an opening therein for the insertion and withdrawal of a pistol, means in said casing to removably hold the pistol therein, a portion of the casing adjacent the opening being cut away to afford protection to a delicate part of the pistol.
12. In a pistol holster, the combination of a casing provided with closed ends and an opening for the insertion and withdrawal of the pistol, apparatus in the casing for removably holding the pistol in the casing and means to prevent the delicate parts of the pistol from engaging the walls of the casing.
13. In a pistol holster, the combination of a casing provided with closed ends and an opening therein for the insertion and withdrawal of the pistol, apparatus including a yieldable resilient member and a catch for removably holding the pistol in the casing, and means to prevent the delicate parts of the pistol from engaging the walls of the casing.
14. In a pistol holster, the combination of a casing formed by coiling a sheet of material on itself and fastening the ends together, end members for the casing, the rear side of the casing being cut away to form an elongated opening for the insertion and withdrawal of the pistol, a block in the top of the casing having a recess therein, a chamber being formed in the bottom of the casing, a spring-pressed plunger in said chamber adapted to engage the muzzle of the pistol and force the butt thereof into said recess, a cam for forcing the pistol butt into said recess and means to prevent the delicate parts of the pistol from engaging the casing walls.
15. In a pistol holster, the combination of a casing provided with an opening in one of its sides intermediate the casing ends for the insertion and withdrawal of the pistol, and a spring in one end of the casing for engaging the muzzle of the pistol and forcing the butt of the pistol into the other end of the casing.
16. In a pistol holster, the combination of a casing provided with an opening intermediate its ends for the insertion and withdrawal of a pistol, spring means in one end of the casing to engage one end of the pistol and force the other end of the pistol into the other end of the casing and cam means to direct the second named end of the pistol into the second named end of the holster.
17. In a pistol holster, the combination of a casing provided with an opening in its rear side for the insertion and withdrawal of a pistol, said opening being intermediate the ends of the casing and leaving chambers in the ends of the casing, spring means in the lower chamber of the casing for engaging the muzzle of the pistol and forcing the butt end thereof into the chamber in the other end of the casing and means to direct the butt end of the pistol into the chamber in the upper end of the holster.

In witness whereof, I have signed my name in the presence of two witnesses this 18th day of February, 1915.

DELBERT H. SNAVELY.
